UNITED STATES PATENT OFFICE.

HENRY TIMKEN, OF ST. LOUIS, MISSOURI.

SPRING-SHACKLE.

SPECIFICATION forming part of Letters Patent No. 341,781, dated May 11, 1886.

Application filed January 27, 1886. Serial No. 189,957. (No model.)

To all whom it may concern:

Be it known that I, HENRY TIMKEN, of the city of St. Louis, in the State of Missouri, have invented a certain new and useful Improvement in Shackles, of which the following is a full, clear, and exact description, reference being had to the accompanying drawings, forming part of this specification, and in which—

10 Figure 1 is a perspective view of my improved shackle, showing the parts disconnected. Fig. 2 is a similar view showing the parts put together. Fig. 3 is a vertical section through the shackle and the side bar or 15 axle of a vehicle to which the shackle is secured.

My invention relates to certain improvements in shackles intended more particularly for use on vehicles; and my invention consists 20 in features of novelty hereinafter fully described, and pointed out in the claims.

Referring to the drawings, A represents a side bar or axle of a vehicle to which my improved shackle may be applied.

25 B represents the body of the shackle, provided with holes C, to receive the usual strap, D, by which it is secured to the side bar or axle, and having a groove, E, to receive the part F of the shackle, as usual.

30 As far as I have yet described, the shackle is of usual form, and such a form as swinging shackles usually have.

Heretofore it has been a source of considerable annoyance to have the part F of the 35 shackle cut into the wooden side bar, against which it bears, and to obviate this difficulty

is the object of my invention; and to this end I make a metal bearing between this part F of the shackle and the side bar by placing a plate, G, in a recess, H, of the body B, that covers the 40 part F of the shackle, as shown, and prevents its cutting into the side bar. I prefer to hold this plate in place by lugs or ribs I, formed upon or secured to the body B, and which are bent over into recesses J in the plate. These recesses J do not, by preference, extend to the 45 bent ends of the plate, so that when the lugs are over into them there is not the slightest danger of the plate moving endwise and losing out when the vehicle is in use.

The ribs are shown in Figs. 1 and 2 before being bent over onto the plate, and in Fig. 3 they are shown bent over.

I claim as my invention—

1. In a shackle, the combination of the body 55 part, swinging part, and plate, the body part having ribs and the plate having grooves or recesses into which the ribs are bent to hold it in place, substantially as and for the purpose set forth.

2. In a shackle, the combination of the body part, swinging part, and plate, the body having a recess to receive the plate over the swinging part and lugs or ribs to hold the plate in place, and the plate having recesses that do 60 not extend its entire length to receive the lugs on the body, bent into said recesses, substantially as and for the purpose set forth.

HENRY TIMKEN.

In presence of—

GEO. H. KNIGHT,
JOSEPH WAHLE.
